UNITED STATES PATENT OFFICE.

ALEXANDER C. OSBORN, OF CLARKSBURG, WEST VIRGINIA.

POST-HOLE AUGER.

SPECIFICATION forming part of Letters Patent No. 310,608, dated January 13, 1885.

Application filed April 4, 1884. (No model.)

To all whom it may concern:

Be it known that I, ALEXANDER C. OSBORN, of Clarksburg, in the county of Harrison and State of West Virginia, have invented certain 5 new and useful Improvements in Post-Hole Augers, of which the following is a full, clear, and exact description.

This invention pertains to an improvement in augers or boring devices for making holes 10 in the ground for the insertion of posts; and the invention consists of the combinations of parts and their construction, substantially as hereinafter fully set forth and claimed.

Reference is to be had to the accompanying 15 drawings, forming a part of this specification, in which similar letters of reference indicate corresponding parts in all the figures.

Figures 1 and 2 represent side elevations, at right angles with each other, of a post-hole 20 auger embodying my invention, the stem of the implement to which the handle or operating-lever is attached being broken away. Fig. 3 is a horizontal section on the line xx in Fig. 1.

A is the stem or central shaft of the auger, 25 pointed, as usual, at its lower end, a . B B are separate cutting-blades or half-disks on opposite sides of the stem, and set inclining in reverse direction to form cutters, each of which is the section of a screw-thread on a side of 30 the axis of the stem opposite to the other, and to allow of proper clearance for the loosened earth up over them, as also through them at their center, where they are formed to leave openings b . These blades B B, which are more 35 or less flexible or elastic, are united, by riveting or otherwise, intermediately of their length, to arms c c , arranged to connect above with opposite sides of the stem, and are further attached near their entering ends by upright 40 braces D D with an upper disk, E, the diameter of which is equal, or thereabout, to the diameter of the screw-blades B B. This disk E is made adjustable up and down the stem

A, passing through its center, and when adjusted is securely held in position by means of 45 upper and lower nuts, G G, arranged to fit a screw-thread, e , on the stem. These nuts, in conjunction with the braces D D, serve to vary the angles of the cutters or to change the relation of them at their entering ends; or, in 50 other words, to adjust the cutters to suit different kinds of soil both stiff and loose. Furthermore, in the operation of the auger by turning it until it stops, when it will be closely packed or filled with the loosened earth between the disk E and cutters B B, the loosened earth or dirt is held in the machine, when or after which the auger is withdrawn from the hole, and the disk prevents the dirt from falling back into the hole. 55

In some cases the pointed end portion of the stem of the bottom of the auger may be in the form of a screw, and may be formed by squaring and twisting it to make the thread. The cutters B B should be larger than the 60 body or frame of the auger and slightly curve upward at their outer edges.

Having thus described my invention, I claim as new and desire to secure by Letters Patent—

1. In a post-hole auger, the combination, 70 with the central stem, of the separate blades having a fixed and an adjustable connection with said stem, the fixed connection being secured to said blades about midway their length, and the adjustable connection being 75 secured to said blades at their entering ends or contiguously thereto, substantially as and for the purpose set forth.

2. The combination, with the stem A and cutters B B, of the disk E, braces D D, and 80 the upper and lower nuts, G G, essentially as and for the purposes herein set forth.

ALEXANDER C. OSBORN.
